UNITED STATES PATENT OFFICE

LEWIS W. HELLER, OF OAK HARBOR, OHIO, ASSIGNOR TO FULLER LEHIGH COMPANY,
OF FULLERTON, PENNSYLVANIA, A CORPORATION OF DELAWARE

FURNACE WALL

Application filed August 21, 1928. Serial No. 301,057.

This invention relates to a furnace wall having sections that are movable relative to each other and in which provision is made for preventing ash or cinders from collecting in the joint between the sections. The invention will be understood from the description in connection with the accompanying drawings in which Fig. 1 is a side view, partly broken away, observed from the inside of the furnace; Fig. 2 is a vertical section, partly broken away through the furnace wall; Fig. 3 is a perspective view of one of the special blocks or tile; and Fig. 4 is a perspective view of a support for the block or tile.

In the drawings, reference character 1 indicates a section of a furnace wall which may be near the lower edge of the wall and may be stationary. Another section of the wall is shown above the section 1 and may be made up of a row of water tubes carrying blocks or tile, this section being supported independently of the lower section and free to move toward and away from the same due to expansion and contraction. The tubes 2 of the water wall have their lower ends bent outwardly, as shown at 3, and are connected to a horizontal header 4 on the outside of the furnace wall. Blocks or tile 5 are connected to the tubes 2 by clamps 6 with bolts 7 connecting the tile 5 and the clamps in the well known way. The tile 5 may be made up with metal backs that have curved surfaces contacting with the tubes 2 and refractory face portions that are exposed to the heat of the furnace.

The upper edge of the wall section 1 is made sloping as indicated at 8 and a flexible metal seal plate 9 is attached to the tubes 2 and its edge rests upon the sloping surface 8 to prevent escape of gases through the joint.

Special blocks or tile are connected to the lower curved portions 3 of the tubes 2 and are located above the section 1 at a sufficient distance therefrom to permit expansion of the upper section of the wall. One of the supports 10 for the special blocks or tile is most clearly shown in Fig. 4. Each support is provided with curved portions 11 to

be clamped into firm engagement with the tubes. A plate 12 extends outwardly toward the inside of the furnace from the lower edge of the support 10 and the free inward edge of the plate 12 is provided with an upwardly extending lip or extension 13. An extension 14 that is T-shaped in cross section projects from the face of the support 10 toward the inside of the furnace and is disposed in a vertically extending direction at an angle 55 to the horizontal when the support 10 is in place.

One of the special blocks or tile 15 that is to be installed in the row near the upper edge of the section 1 of the furnace wall is 60 most clearly shown in Fig. 3. Each one of the special tile or blocks is provided with a flat back portion that fits against the front face of the support 10. Each special block is of an approximate V-shape having a front face 16 that is vertical and in line with the inner face of the section 1 when the blocks are in place, as most clearly indicated in Fig. 2. The lower end of the block 17 is somewhat pointed and the bottom of the block is 65 flat and approximately parallel with the sloping surface 8 of the section 1 when the block is in place. A recess 18 is provided in the bottom of each block into which the corresponding plates 12 and lips 13 of the supports 10 fit when the blocks are installed. Each block is provided with a T-shaped recess 19 into which the corresponding extensions 14 fit.

It will be obvious from an inspection of 85 Figs. 3 and 4 that the blocks 15 can be put in place on the supports 10 by moving the same downwardly for the extensions 14 to fit into the grooves 19 and the plates 12 and lips 13 to fit into the recesses 18, thus holding the blocks securely in position by means of the supports 10, and at the same time making it possible to remove them very readily for replacement when injured or broken.

With the cap or joint between the two sections of the furnace wall sloping downwardly, as most clearly shown in Fig. 2, it will 90 be clear that any ash or cinders that may be caught in this space will work downwardly and into the furnace as expansion and con- 100

traction take place between the sections, and that the danger of the joint becoming permanently clogged with the ash and cinders is eliminated.

5 The upper surface of the blocks 15 may be made horizontal so that the next row of blocks may rest thereon, and the blocks that are attached to the curved portions of the tubes 2 may be so shaped that a flat surface is presented to the inside of the furnace.

I claim:

1. In a furnace, a wall section and a second wall section above said first-named wall section, one of said wall sections being movable relative to the other, adjacent portions of said wall sections forming a space downwardly inclined toward the furnace to prevent ash or clinker from collecting between said wall sections.

20 2. In a furnace, a wall section, and a second wall section above said first-named wall section, one of said wall sections being movable relative to the other, one of said wall sections being water-cooled, adjacent portions 25 of said wall sections forming a space downwardly inclined toward the furnace to prevent ash or clinker from collecting between said wall sections.

30 3. In a furnace, a wall section and a second wall section above said first-named wall section, one of said wall sections being movable relative to the other, adjacent portions of said wall sections forming a space downwardly inclined toward said furnace to prevent ash or clinker from collecting between said sections, the upper portion of said second wall section comprising a block having a portion of its upper surface extending downwardly and inwardly toward the furnace.

40 4. In a furnace, a wall section, a second wall section above said first-named wall section comprising tubes and tile attached thereto, said wall sections being spaced apart and independently supported, adjacent portions of 45 said sections forming a space extending downwardly into a free space to prevent ash or clinker from collecting between said sections, and means to prevent gas leakage from 50 taking place through said space.

LEWIS W. HELLER.
